W. T. SEARS.

COUNTERBALANCING MECHANISM FOR DRILLING MACHINES.

APPLICATION FILED MAY 9, 1918.

1,329,726.

Patented Feb. 3, 1920.

UNITED STATES PATENT OFFICE.

WILLARD T. SEARS, OF BROOKLYN, NEW YORK, ASSIGNEE TO NILES-BEMENT-POND COMPANY, OF NEW YORK, N. Y., A CORPORATION OF NEW JERSEY.

COUNTERBALANCING MECHANISM FOR DRILLING-MACHINES.

1,329,726.

Specification of Letters Patent. Patented Feb. 3, 1920.

Application filed May 9, 1918. Serial No. 233,405.

To all whom it may concern:

Be it known that I, WILLARD T. SEARS, a citizen of the United States, residing at Brooklyn, in the county of Kings and State 5 of New York, have invented certain new and useful Improvements in Counterbalancing Mechanisms for Drilling-Machines, of which the following is a specification.

The invention is particularly applicable 10 to universal radial drilling machines in which the spindle is angularly adjustable with respect to the arm and in which the arm is angularly adjustable with respect to the column; but the invention can also be 15 used for a plain radial drilling machine. The invention relates to a counterbalancing device of the class in which the counterweight is movable longitudinally parallelly with the spindle but in the opposite direction, the line of movement of the counterweight being adjusted angularly in accordance with the angular adjustment of the spindle. In accordance with the invention, 20 the counterweight is connected with the spindle by gearing, this gearing engaging a 25 rack on the counterweight which is so located that its central pitch line passes through the center of gravity.

In the accompanying drawing I have 30 shown two embodiments of the invention, either of which may be used as required to meet the conditions of a particular design. It will be understood, however, that the drawing is intended to be merely illustrative 35 and that there may be many variations, particularly in the general arrangement and construction of parts, without departing from the spirit of the invention as set forth in the appended claims.

40 Of the drawing:

Figure 1 is a side view of a drilling machine embodying the invention.

Fig. 2 is an end view.

Fig. 3 is a fragmentary horizontal sectional view taken along the lines 3-3 of Figs. 2 and 4.

Fig. 4 is a fragmentary elevational view of the parts shown in Fig. 3.

Fig. 5 is a view similar to Fig. 3 but showing another embodiment of the invention.

Fig. 6 is a fragmentary sectional view taken along the line 6-6 of Fig. 5.

Referring to the drawing, 1 represents the main column of the machine, this column being mounted on a base 2 so as to be capable

of angular movement about a vertical axis. Preferably the column is formed in two parts, as set forth in my patent for radial drills No. 1,071,590 dated August 26th, 1913. A carrier frame 3 is mounted between the two parts of the column and is vertically adjustable. A horizontal arm 4 is secured to the member 3 at one side thereof, and a main arm shaft 5 extends longitudinally of the arm. Preferably the arm 4 is angularly adjustable with respect to the member 3 about the axis of the shaft 5. Secured to the member 3 at the side opposite the arm is a casing 6 and a motor 7. Suitable gearing is provided in the casing 6 for driving the arm shaft 5.

Carried by the arm and preferably longitudinally movable therealong is a saddle 8. Secured to the saddle is a head 9 which is angularly adjustable about a horizontal axis 75 perpendicular to the axis of the shaft 5. Mounted in the head 9 is a spindle 10 which is normally vertical, as shown in the drawing, but which is angularly adjustable with the head. The drill is secured to this spindle in any usual or preferred way. The spindle 10 is longitudinally movable to bring the drill into operative position or to effect feeding. The spindle is rotated from the shaft 5 in the usual way by means of 80 bevel gearing 11, the initial driving element of this gearing being splined on the shaft 5 and the final driven element thereof being splined on the spindle 10. This gearing permits the saddle to be moved longitudinally of the arm, or the spindle to be moved longitudinally of the head, or the head to be adjusted angularly with respect to the saddle.

For effecting longitudinal movement of the spindle there is provided a non-rotary sleeve 12 which surrounds the spindle and is connected for longitudinal movement therewith. This sleeve is provided with rack teeth 13 which mesh with a pinion 14 on a horizontal shaft 15 rotatably mounted in the upper part of the head 9. Means is provided for rotating the shaft 15, this means, as shown, including a bevel gear 16 on the shaft which meshes with a bevel gear 17 on an inclined shaft 18. At the lower end of the shaft 18 are suitable devices whereby the shaft may be turned either manually or by power to effect longitudinal movement of the spindle. For feeding during the drilling 110

operation, the power devices are preferably thrown into operation. These devices do not of themselves constitute any part of the present invention and they are not therefore 5 shown or described in detail.

For counterbalancing the spindle I provide a counterweight 19 or 19^a which is guided for movement along the head parallelly with the spindle 10. This counterweight has secured to it a longitudinal rack 20 or 20^a. The counterweight is so shaped and the rack is so positioned that the central pitch line of the rack extends through, or approximately through, the center of 15 gravity.

Gearing is interposed between the spindle and the rack of the counterweight whereby the counterweight and the spindle are made to move in opposite directions, the 20 weight thus serving to counterbalance the spindle. Preferably use is made in part of the same gearing which serves to move the spindle longitudinally for adjustment or for feeding. Preferably, a gear 21 is secured to 25 or formed as a part of the shaft 15. As illustrated in Figs. 3 and 4, the gear 21 meshes directly with the rack 20. As illustrated in Fig. 5, a pinion 21 meshes with an idler gear 22, this idler gear meshing in 30 turn with the rack 20^a. Preferably the pinion 21 is of smaller diameter than the pinion 14, thus causing the counterweight to have a shorter range of movement than the range of movement of the spindle.

35 The head 9 is provided with a guide which engages the counterweight. Preferably this guide is located immediately adjacent the rack and is therefore close to the center of gravity of the counterweight. As illustrated in Fig. 3, there is a guide 23 which projects into a longitudinal groove in the counterweight. The groove is immediately adjacent the rack 20 so that the body of the rack also engages the guide. As illustrated in Fig. 5, there is a guide 23^a, which engages longitudinal surfaces on the counterweight and on the body of the rack 20^a.

It will be clear that with either construction shown the counterweight serves to counterbalance the drill spindle for all positions thereof, the line of movement of the counterweight being always parallel with the line of movement of the spindle. The 50 counterweight is supported by the pinion 21 or 22 which engages the rack thereof and, inasmuch as the pitch line of the rack extends through the center of gravity, the counterweight is always supported at its 55 center of gravity. There is therefore little or no tendency for the counterweight to clamp or bind its guide and it therefore moves with a minimum frictional resistance.

The possibility of clamping or binding is 60 still further reduced by the location of the

guide as near as possible to the rack and thus close to the center of gravity.

By comparing Figs. 3 and 5 it will be seen that in one construction the rack is located at the front of the shaft 15 and in 70 the other construction at the back of the shaft 15. This change in the location of the rack requires corresponding changes in the shape and position of the counterweight in order that the center of gravity may in 75 both cases be at the pitch line of the rack. Either construction may be used, as required.

What I claim is:

1. In a drilling machine, the combination with the spindle, of a counterweight movable in parallelism to the spindle, a longitudinal rack secured to the counterweight with its central pitch line extending through the center of gravity thereof, and 80 gearing connected with the spindle and engaging the rack.

2. In a drilling machine, the combination with the spindle, of a counterweight movable in parallelism to the spindle, a longitudinal rack secured to the counterweight with its central pitch line extending through the center of gravity thereof, gearing connected with the spindle and engaging the 85 rack, and a guide engaging the counterweight along lines immediately adjacent the rack.

3. In a drilling machine, the combination with the spindle, of a counterweight movable in parallelism to the spindle, a longitudinal rack secured to the counterweight with its central pitch line extending through the center of gravity thereof, gearing connected with the spindle and engaging the 100 rack, and a guide engaging the body of the 105 rack and engaging the counterweight along lines immediately adjacent the rack.

4. In a radial drilling machine comprising a vertical column, an arm carried by the column and a longitudinally movable 110 spindle carried by the arm, the combination with the spindle, of a counterweight movable in parallelism to the spindle, a longitudinal rack secured to the counterweight with its central pitch line extending through 115 the center of gravity thereof, and gearing connected with the spindle and engaging the rack.

5. In a radial drilling machine comprising a vertical column, an arm carried by 120 the column, and a longitudinally movable spindle carried by the arm, the combination with the spindle, of a counterweight movable in parallelism to the spindle and partially surrounding it, a longitudinal rack 125 secured to the counterweight with its central pitch line extending through the center of gravity thereof, and gearing connected with the spindle and engaging the rack.

6. In a radial drilling machine compris- 130

ing a vertical column, an arm carried by the column and an angularly adjustable longitudinally movable spindle carried by the arm, the combination with the spindle, of a 5 counterweight movable in parallelism to the spindle and angularly adjustable therewith, a longitudinal rack secured to the counter-

weight with its central pitch line extending through the center of gravity thereof, and gearing connected with the spindle and engaging the rack. 10

In testimony whereof, I hereto affix my signature.

WILLARD T. SEARS.
